UNITED STATES PATENT OFFICE.

JOHN A. FINDORA, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

MACHINE FOR SHORTENING SPRINGS.

Application filed November 27, 1923. Serial No. 677,237.

This invention relates to the manufacture of springs, and more particularly to machines for shortening the normal overall length of coil springs of the type known as bed-springs.

Springs of this type generally diminish in diameter from the ends to the middle of the spring, and at the time they are received from the coiling machine they are of greater overall length than is desired in the finished product.

An object of this invention is to provide a machine for compressing or shortening the overall length of springs of the above type without in any way injuring their resilient qualities.

A further object is to provide a machine for this purpose which is continuous in operation and may be easily operated by unskilled labor.

A still further object is to provide such a machine which has few and simple parts and which is rugged in construction and positive in operation.

These and other objects which will be apparent to those skilled in this particular art I attain by means of my invention, one embodiment of which is shown by way of example in the accompanying drawing in which Fig. 1 is a front elevational view of a machine constructed in accordance with this invention, Fig. 2 is a view in side elevation of the machine shown in Fig. 1, Fig. 3 is a vertical sectional view of the work-holder showing the compressor head in its extreme spring-compressing position, Fig. 4 is a view in horizontal section on the line 4-4 of Fig. 2, and Fig. 5 is an enlarged view of the driving means for the rotary work-holder.

The machine illustrated includes an upright supporting member 10 having a drive shaft 11 mounted in bearings 12 at the top thereof. At one end of the shaft is a driving pulley 13 driven by a belt 14 from any suitable source of power (not shown). A crank arm 15 is secured to the opposite end of the shaft 11 and is connected through the medium of a connecting rod 16 with a reciprocable compressor head 17.

The compressor head 17 is mounted to reciprocate on ways 18 formed on the front of the upright supporting member 10 and it

is guided in its movements by a guide bar 19 extending through a perforation 20 in 55 the compressor head and secured to the supporting member 10 by brackets 21 and 22.

The compressor head 17 has a sleeve 23 mounted therein and a compressor plate 24 having a flange 24' for centering the spring 60 during compression is screw threaded to the lower part of the sleeve 23. The compressor plate is provided with a central opening 25 opening into the interior of the hollow sleeve for a purpose to be hereinafter described.

A stub shaft 26 supports a rotary work holder which is in the form of a disk 27 having a flange 27' provided with equally spaced circumferential holes 27''. Radially 70 extending spring supporting fingers 28 are provided with reduced extensions 28' which fit the holes 27'' of the work holder in which the fingers are secured. Spring seats 29 are clamped between the flange 27' of the work 75 holder and the enlarged part of the fingers 28. Each spring seat has a flange 29' which cooperates with the flange 24' on the compressor plate to center the springs during compression.

The work-holder is rotated intermittently and in synchronism with the reciprocations of the compressor head through the medium of a common single tooth Geneva movement which includes a driving gear 30 mounted 85 on a suitable shaft 31 and provided with a drive tooth 32 adapted to intermittently rotate a gear 33 connected to the hub of the work holder 27. The gear 33 has notches 34 for engagement with the driving tooth 32 and concave locking surfaces 35 adapted to cooperate with a convex locking surface 36 on the driving gear 30 during that part of the movement in which the tooth 32 is out of engagement with the notches 34.

The Geneva movement is driven from the main shaft 11 through the medium of a driving chain 37 which drives a sprocket 38 on the shaft 31.

A chain tightener is provided which comprises a small sprocket 39 in mesh with the chain 37. The sprocket is supported upon an arm 40 secured to the frame 10 by a bolt 41 about which it may be adjusted to different positions so as to vary the tension of 105 the chain 37.

The effective stroke of the compressor head 17 may be varied by securing the connecting bar 16 at different points on the crank arm 15. A plurality of holes 42 are provided 5 in the crank arm for this purpose.

Assuming that the drive shaft 11 is rotating in the direction indicated by the arrow in Fig. 1, the elongated springs received from the coiling machine are placed on the 10 fingers 28 by the operator as each finger is presented to him. The next movement or partial rotation of the work holder moves the finger and the supported spring into vertical position. The compressor head 17 15 then descends and the spring is compressed between the supporting plate 29 and the compressor plate 24 beyond its elastic limit so that upon retraction of the compressor head the spring does not resume its original 20 length but assumes a reduced or shortened overall length. During compression of the spring it is centered and held in proper position by the cooperating flanges on the compressor plate and on the spring seat. The 25 finger 28 is accommodated by the hollow sleeve 23 and the hole 25 in the center of the compressor plate 24. As the work holder is rotated further to present fresh springs to the compressor head the shortened springs 30 drop off the fingers by gravity and in this way unencumbered fingers are continually presented to the operator for the reception of fresh springs.

Having thus described one embodiment of 35 my invention, what I claim and desire to secure by Letters Patent is:

1. A machine for compressing helical springs, having in combination a reciprocable compressor head, a work-holder including a flanged disk, work-supporting fingers projecting from the flange thereof, and means for intermittently rotating said work-holder in synchronism with the reciprocations of said head for successively presenting 45 springs thereto.

2. A machine for compressing helical springs, having in combination a reciprocable compressor head, a work-holder including a flanged disk provided with radially extending work-supporting fingers, means for intermittently rotating said work-holder in synchronism with the reciprocations of said head for successively presenting springs thereto, and means for centering 50 and positioning said springs during compression.

3. A machine for compressing helical springs, having in combination a reciprocable compressor head provided with a 60 flanged compressor plate, a rotary work-holder including a flanged disk having radially projecting work-supporting fingers secured thereto, a spring seat mounted at

the base of each finger having a flange adapted to cooperate with said flanged compressor plate for centering the springs during compression, and means for intermittently rotating said work-holder to successively present springs to said compressor plate.

4. In a machine for compressing helical springs, having in combination a reciprocable compressor head, a shaft for operating said head, a work-holder for positioning springs in operative relation to said head, 70 a shaft parallel to said operating shaft for supporting said work-holder in operative relation to said head, and mechanism for driving said shafts so as to operate said work holder in timed relation to the reciprocations of said head.

5. A machine for compressing helical springs, having in combination a reciprocable compressor head, a work-holder rotatable about a horizontal axis and provided with radially-projecting work-supporting fingers, a shaft for operating said compressor head, a Geneva movement for operating said work-holder, and means for driving said Geneva movement from said shaft.

6. A machine for compressing helical springs, having in combination two parallel shafts, a reciprocable compressor head adapted to be operated by one of said shafts, a rotary work-holder adapted to be intermittently rotated by the other of said shafts and having a plurality of radially-extending work-supporting fingers, and mechanism for driving said shafts so as to rotate said work-holder in timed relation to the reciprocations of said head.

7. A machine for compressing helical springs, having in combination a reciprocable compressor head, a work-holder including a disk provided with a perforated annular flange, work supports secured in the perforations of said flange, and means for intermittently rotating said work-holder in synchronism with the reciprocations of said head for successively presenting springs thereto.

8. A machine for compressing helical springs, having in combination a reciprocable compressor head, a work-holder including a disk provided with an annular perforated flange, work-supporting fingers secured in the perforations of said flange so as to extend radially outward therefrom, and means for intermittently rotating said holder in synchronism with the reciprocations of said head for successively presenting springs thereto.

In testimony whereof, I have hereunto subscribed my name this 22nd day of November, 1923.

JOHN A. FINDORA.
